UNITED STATES PATENT OFFICE

GEORGE C. MILLER, OF BRIGHTON, MASSACHUSETTS

DISPLAY DEVICE

Application filed May 26, 1930. Serial No. 455,622.

This invention relates to display devices and particularly to a display cabinet which includes not only a display area adapted advantageously to disclose articles of many sizes and shapes, but also produces a readily accessible storage space for other stock or supplies than those on immediate display.

In display structures of cabinet form heretofore in use, the display portions have been so disposed that the storage of stock was impossible without either decreasing the display itself or having the stored stock visible through the display openings. In my present invention I have overcome these difficulties by so proportioning and arranging the parts that a considerable storage space is provided without interfering with or lessening the display area. This I accomplish in part by employing what I term a terraced arrangement of display areas.

Furthermore, my invention is so constructed that the same may readily be cleaned without the necessity of making the many compartments removable.

The framework, enclosing members and shelves of my cabinet are made of sheet metal so designed as to provide a ready assembly and convenient replacement of parts, said parts being of such overlapping and interfitting nature as to act as reinforcements for each other to the end that a finished structure of great strength and compact nature is produced.

Throughout the specification and drawings like reference numerals are employed to indicate corresponding parts.

In the drawings:

Fig. 1 is a front elevation of my cabinet.

Fig. 2 is a side elevation.

Fig. 3 is a section on the line 3—3 of Fig. 1.

Fig. 4 is a back elevation, part of the lower portion being broken away to disclose the compartment construction, and

Fig. 5 is a top plan view partly broken away to show the means for holding the front doors in closed position.

My cabinet comprises a support 1 having legs 1¹ provided with upturned inwardly disposed flanges 1² adapted to be screwed or otherwise attached to the floor of the chest C,

which floor is disclosed as a wooden member 2, although the same, if desired, may be of sheet metal or any other suitable material. Resting on said bottom 2 are the inturned flanges 3¹ of a back panel 3 for the lower or chest portion of my display device, said panel 3 having also an upper inturned flange 3² (see Fig. 3).

The side panels 4 are provided with inturned side portions 4¹ which overlap and brace the back panel 3 (see Fig. 4).

Adjoining the side panels 4 are front panels 5. The panel 5 is cut away to provide an entrance E which may be closed by doors D hinged to the panel 5 at 5² and which are separated from each other by a vertical panel 6 spaced inwardly from the panel 5 and having inturned flanges 6¹.

The door D comprises an outer metal panel D¹ having rolled or beaded edges D^a and an inner spaced metal panel D², the same having inwardly and outwardly turned flanges D^b adapted to enter the beaded edges D^a of the panel D. The space between these panels is filled with wood W or other suitable material. The inner panel enters and passes through the entrance E, and the panels D² overlap the same.

A reinforcement for the back 3 and bottom 2 is provided. This comprises a sheet metal piece 7 folded to fit the inside walls and providing a pocket 7¹ adapted to receive the forward end of the floor-board 2. The top of the lining 7 has an inturned flange 7². The chest C is divided vertically as at 8 and horizontally as at 8¹ to provide four compartments. The vertical partition 8¹ has inturned flanges at its top and bottom which bear against the inturned flanges 8^a, the lower one of which bears against the lining 7 for the floor 2 and the upper one bears against and supports the top wall of the cabinet 9.

The horizontal partition 8 is subdivided and has downturned flanges 8^b, the inner of which bear against the vertical partition 8¹ and the outer of which bear against the side walls 4.

The door portions D¹ near their inner edges are provided with handles 10 which have inwardly extending portions 10¹ adapted to be

engaged by spring arms 11 mounted on the front edge of the horizontal partition 8 on either side of the vertical panel 6, this arrangement providing a spring catch adapted to hold the doors in closed position.

5 The top 9 has an upwardly extending guard 9¹ (see Fig. 3) about the front and sides thereof, the front portion of which is adapted to engage the inturned portion or bead 5¹ of the top of the piece 5. The top panel is 10 provided with an opening or slot S just inwardly of the front panel 5 for a purpose hereinafter to be disclosed.

Above and supported by the chest C is 15 disposed my terraced display which I have indicated generally at A. This comprises side panels 12 which are bent upon themselves to form flanges 13. The side panels are riveted as at R, Figs. 2 and 3, to the guard 9¹.

20 The upper portion of the back of the display A is closed by panels 34² and 28³ which lie beneath and are riveted to the flanges 13 of the sides 12. Beneath these panels is an 25 opening 15 through which access is had to the storage area 22 rearwardly of the lower portions of the display A. This opening 15 is closed by a sliding door 16 which slides within guideways 17 which extend along either 30 side of the opening 15. At the top of the door 16 is a handle 18 and attached chain or cord 19 having a hook 20 adapted to engage the edge of the top 21 of the display A which has a beaded edge 21¹. At its front edge the 35 top 21 which rests on the top edges of the sides 12, extends as a downturned finishing flange 21².

Separating the storage area 22 from the lowest display section 23 is a vertical partition 24 which has an inturned flange 24¹ thereabouts through which flange said partition 24 is riveted to the sides 12 and the top 9 and superposed display section 25.

This second tray section 25 is supported by angle irons 27 fastened to the inside of the 45 walls 12 and also by the upper inturned flange 24¹ of the partition 24.

The back and bottom of the tray 25 are composed of a single piece of metal and the back 25¹ serves as a further partition separating the storage space 22 from the display trays or sections 23 and 25.

This tray back 25¹ is turned horizontally 50 at its top and enters a pocket defined by the inturned horizontal edge 28² of the bottom 28¹ of the tray 28, which bottom is supported by angleirons 29 carried by the inside walls of the panel 12. The bottom 28¹ is inclined and extends upwardly as at 28³, the sides of the tray 28 being provided by the wall 12 which is cut away to conform to the inclination of the trays as is shown in Fig. 3. A glass front 30 is held by angleirons 31 also carried by the walls 12. As the inclined floor 65 28¹ is of considerable area this may be sub-

divided by a partition in the form of an angleiron 32.

By reference to Fig. 3 it will be noted that the inclined member 28¹ acts as a top for the storage compartment 22. This storage compartment 22 is thus entirely separated from the front or display portion of the cabinet by the upright 24, the bottom and back of the tray 25 and the inclined bottom 28¹ of the tray 28.

75 Supported by the inturned flange 28⁴ and angleirons 33 is an inclined display section 34 which, however, extends from the vertical at a less acute angle than the tray 28 so as not to interfere with the view of the goods on display therein. This section 34 has also a glass front 35 supported by angleirons 36 and is subdivided by an angleiron 37. The floor 34¹ extends upward to form a back 34² having an inturned edge 34³ on which the top 21 80 rests.

85 By reference to Figs. 2 and 3 it will be seen that each ascending tray terminates inwardly short of the tray just below, thus permitting an unobstructed view of the many items which may be arranged in the several display sections. In the case of the sections 23 and 25 which have flat bottoms, an upturned metal rim is sufficient to prevent the goods slipping from the trays. On the inclined sections, the glass fronts serve not only to prevent the goods sliding from position but also creates an impression of what appears to be a gradually rising and unbroken display of goods.

90 On the top shelf 21 may be arranged the larger articles or the same may be utilized for any other purpose for which a shelf is adapted.

95 As cut away, the sides 12 serve as end supports or sides for the several display sections but do not interfere with the display itself. Furthermore, these cut-away sides permit a readier access to the goods than otherwise would be possible.

100 The trays may be subdivided to any desired number or any desired shape and in Fig. 5 I have illustrated the two lower trays as each being sub-divided into seven similar compartments 40.

105 In the case of the inclined trays 28 and 34, the glass and angleiron partitions may readily be removed and the trays dusted or swept out. In the case of the flat bottom displays 23 and 25, I have provided in the front edge of each slot S through which the dust or other matter which may have accumulated on the bottom of the tray may be swept.

110 Various modifications in the construction of my display cabinet, the manner of erecting the same, the arrangement and relation of the display and storage sections, and the manner of supporting each part in relation to the others may obviously be varied without de-

parting from the spirit of my invention if within the limits of the appended claims.

What I therefore claim and desire to secure by Letters Patent is:

- 5 1. Display apparatus comprising a support having an upturned rim, back and sides attached to said rim and supported thereby, a vertical partition spaced inwardly from the front of said rim and supported by said sides
 10 and providing with said rim a front display section, said partition having an inturned flange on its upper edge, a second display section consisting of a member bent to provide a vertical back and horizontal bottom, a forwardly turned flange on said back, said section supported by said sides with its bottom bearing on said inturned flange of said partition and disposed so that said bottom extends forwardly of said vertical partition to provide a partial cover for said front display section, a third display section comprising a member bent upon itself to provide an inclined bottom and a vertical back, said bottom having a horizontally disposed pocket
 15 adapted to receive the forwardly turned flange of said second display section and said back having a forwardly turned flange, the bottom of said third section extending over said second section to provide a partial cover
 20 therefor but terminating inwardly of the front thereof.
2. Display apparatus comprising a support having an upturned rim, back and sides attached to said rim and supported thereby, a vertical partition spaced inwardly from the front of said rim and supported by said sides and providing with said rim a front display section, said partition having an inturned flange on its upper edge, a second display section consisting of a member bent to provide a vertical back and horizontal bottom, a forwardly turned flange on said back, said section supported by said sides with its bottom bearing on said inturned flange of said partition and disposed so that said bottom extends forwardly of said vertical partition to provide a partial cover for said front display section, a third display section comprising a member bent upon itself to provide an inclined bottom and a vertical back, said bottom having an inwardly disposed horizontal pocket adapted to receive the forwardly turned flange of said second display section and said back having a forwardly turned flange, the bottom of said third section extending over said first section to provide a partial cover therefor but terminating inwardly of the front thereof, a fourth display section comprising a member bent to provide a vertical back and inclined bottom, said bottom terminating inwardly of the bottom of said third display section and said bottom at its rear bearing on said inturned flange of said third section, said fourth section being mounted on said sides at an angle thereto other than the angle of said first and second sections, and a cover supported by said sides and having its rear end bearing on said inturned flange of said fourth section and terminating inwardly of the bottom of said fourth section.
3. Display apparatus comprising a support having an upturned rim, back and sides attached to said rim and supported thereby, a vertical partition spaced inwardly from the front of said rim and supported by said sides and providing with said rim a front display section, said partition having an inturned flange on its upper edge, a second display section consisting of a member bent to provide a vertical back and horizontal bottom, a forwardly turned flange on said back, said section supported by said sides with its bottom bearing on said inturned flange of said partition and disposed so that said bottom extends forwardly of said vertical partition to provide a partial cover for said front display section, a third display section comprising a member bent upon itself to provide an inclined bottom and a vertical back, said bottom having an inwardly disposed horizontal pocket adapted to receive the forwardly turned flange of said second display section and said back having a forwardly turned flange, the bottom of said third section extending over said first section to provide a partial cover therefor but terminating inwardly of the front thereof, a fourth display section comprising a member bent to provide a vertical back and inclined bottom, said bottom terminating inwardly of the bottom of said third display section and said bottom at its rear bearing on said inturned flange of said third section, said fourth section being mounted on said sides at an angle thereto other than the angle of said first and second sections, and a cover supported by said sides and having its rear end bearing on said inturned flange of said fourth section and terminating inwardly of the bottom of said fourth section.
4. Display apparatus comprising a support having an upturned rim, back and sides attached to said rim and supported thereby, a vertical partition spaced inwardly from the front of said rim and supported by said sides and providing with said rim a front display section, said partition having an inturned flange on its upper edge, a second display section consisting of a member bent to provide a vertical back and horizontal bottom, a forwardly turned flange on said back, said section supported by said sides with its bottom bearing on said inturned flange of said partition and disposed so that said bottom extends forwardly of said vertical partition to provide a partial cover for said front display section, a third display section comprising a member bent upon itself to provide an inclined bottom and a vertical back, said bottom having an inwardly disposed horizontal pocket adapted to receive the forwardly turned flange of said second display section and said back having a forwardly turned flange, the bottom of said third section extending over said first section to provide a partial cover therefor but terminating inwardly of the front thereof, a fourth display section comprising a member bent to provide a vertical back and inclined bottom, said bottom terminating inwardly of the bottom of said third display section and said bottom at its rear bearing on said inturned flange of said third section, said fourth section being mounted on said sides at an angle thereto other than the angle of said first and second sections, and a cover supported by said sides and having its rear end bearing on said inturned flange of said fourth section and terminating inwardly of the bottom of said fourth section.

forwardly turned flange, the bottom of said third section extending over said first section to provide a partial cover therefor but terminating inwardly of the front thereof a fourth display section comprising a member bent to provide a vertical back and inclined bottom, said bottom terminating inwardly of the bottom of said third display section and said bottom at its rear bearing on said inturned flange of said third section, said fourth section being mounted on said sides at an angle thereto other than the angle of said first and second sections, and a cover supported by said sides and having its rear end bearing on said inturned flange of said fourth section and terminating inwardly of the bottom of said fourth section, said sides being cut away substantially to conform to the end contour of said display sections so that the goods on display may be seen and removed from the side as well as the front of the display apparatus.

In testimony whereof I affix my signature.

GEORGE C. MILLER.
